UNITED STATES PATENT OFFICE.

FREDERIC E. TOWN, OF GLEN CARLYN, VIRGINIA.

ELECTRIC-METERING SYSTEM.

SPECIFICATION forming part of Letters Patent No. 654,498, dated July 24, 1900.

Application filed May 11, 1900. Serial No. 16,349. (No model.)

To all whom it may concern:

Be it known that I, FREDERIC E. TOWN, a citizen of the United States, residing at Glen-
5 carlyn, in the county of Alexandria and State of Virginia, have invented certain new and useful Improvements in Electric-Metering Systems, of which the following is a specification.

My present invention pertains to an im-
10 proved electric-metering system, the arrange-
ment and advantages of which will be here-
inafter set forth, reference being had to the
annexed drawings, wherein—

Figure 1 is a plan view showing the arrange-
15 ment of circuits and so much of a main and auxiliary meter as is necessary to a proper illustration of the invention; Fig. 2, a detail view of the contact making and breaking device; Fig. 3, a side elevation, partly in sec-
20 tion, of a modified form of contact device; Fig. 4, a top plan view of the same; Fig. 5, a side elevation of a modified form of apparatus used to actuate the auxiliary or maximum load meter or registering device; Fig. 25 6, a top plan view of the same; Fig. 7, a dia-
grammatic view illustrating the apparatus used on an independent circuit; and Fig. 8, a similar view illustrating an arrangement of primary meters, together with certain auxiliary or secondary meters, for a purpose which
30 will be hereinafter described.

Many attempts, more or less successful, have heretofore been made to provide a system for properly and accurately registering the con-
35 sumption of current or energy during a stated interval of time—generally during that period of the service known as the “peak” or height of the load. To encourage the use of the current during that period when the load is
40 usually low is the aim of most electric plants, and it is of course desirable to have a double metering or registering system to effect a registration for both periods, so that a discount may be made for one period and the maxi-
45 mum charge made for the other.

The main object of my present invention is to provide a simple and efficient means for bringing about this multiple or double registration, and although this is the primary ob-
50 ject, still the system has other advantages and uses, as will be hereinafter more fully set forth and explained.

The invention in its breadth comprises a circuit in which is included an electrically-actuated device for operating an auxiliary 55 registering mechanism and a make-and-break device carried by a moving part of the usual or ordinary meter adapted to periodically close the circuit, thereby permitting current to pass to line, which brings the electrically- 60 actuated device into operation and in turn effects registration in the auxiliary registering mechanism.

Referring to the drawings, and more par-
ticularly to Fig. 1 thereof, A denotes a por-
tion of the dial of any well-known and ac-
cepted type of meter included in the service-
line and constantly running when current is
used, registering the total consumption. B is
one of the gears thereof, and C the worm-
70 shaft meshing therewith, said shaft deriving
its motion from the current-measuring de-
vices, as is well understood.

Gear B carries an arm D, mounted in an insulated bushing, the arm by preference being bent, as indicated in Fig. 2, so that its outer end will be at a distance from the axis of the gear, this for the purpose of making a quick make and break with the contact arms or brushes E and F, with which it comes into 80 contact once for each revolution of said gear. Said contact-brushes are carried by an insulating-block G or other similar support. Binding-posts are provided for these brushes, one being connected by a conductor H to one 85 of the meter-terminals and the other connected to conductor I, which leads to an electromagnet J. The opposite side of the magnet or winding thereof is in turn connected by a wire K' to a branch or control 90 wire K, which may lead to any desired point, such as the main station or a substation, where it is connected to one pole of a switch L, the opposite pole being connected to a bus or feeder. Other meters may be similarly 95 connected to auxiliary registering devices, which in turn may be connected to the control-wire K. From this it will readily be seen that only one control-wire is necessary for the entire system.

100 The electromagnet is preferably carried by a suitable support or plate M of the auxiliary registering device, the dials of the device being indicated in dotted lines, Fig. 1. The

main shaft of said auxiliary register has connected to it a star-wheel N, while pivoted to the plate M, to one side thereof, is a pallet O, having connected to it or formed integral therewith an armature P.

By reason of the peculiar construction of the pallet as shown—that is, by making one arm longer than the other and properly proportioning the working faces of its ends—said pallet may be made to actuate the star-wheel step by step and to lock the same against overthrow, the magnet and armature serving to move it in one direction and spring Q in the opposite direction as soon as the circuit is broken and the current ceases to flow.

Assuming that current is being used and it is desired to measure it for a stated period or interval of time, the attendant has simply to close the circuit by means of switch L, and for each revolution of gear B there will take place an actuation of the pallet, and consequently the star-wheel will be moved forward one step, causing a corresponding movement of the auxiliary registering device. When the period for which it was desired to secure the separate reading has elapsed, it is only necessary to open switch L. The main meter will continue to register, and there is of course secured a reading for the fixed interval, as well as a reading for the total consumption.

In Figs. 3 and 4 there is illustrated a construction designed to take the place of the arm D. It consists simply of a disk R, of wood or other non-conducting material, which may be secured upon the shaft carrying the gear B and which has set in its periphery a conducting-strip S, adapted to make contact with the brushes E and F once for each revolution of the shaft. It is obvious that many forms and arrangements of such parts will suggest themselves whereby the same result may be accomplished, and the two forms herein shown are to be taken simply as illustrative.

It is manifest that the circuit-closing device may be attached to any movable part of the main or service meter, and I desire to be understood as not confining myself to the particular arrangement shown.

In Figs. 5 and 6 a modified form of actuating device for the auxiliary register is shown. It comprises a solenoid T, included in the circuit, having its core connected to one end of a pivoted lever U, said lever carrying at its opposite end a pawl V, arranged to act in conjunction with a ratchet-wheel W, corresponding to the star-wheel N in the auxiliary meter-train. A detent X is employed to prevent return movement of the ratchet-wheel, and a spring Y is used to act upon the lever in opposition to the solenoid. The action of this arrangement of parts is obvious. This, too, is merely illustrative of a different embodiment of this part of my invention over that shown in Fig. 1, and it is apparent that any suitable form of electric-

ally-actuated mechanism may be employed for bringing about the registration in the auxiliary meter or registering mechanism.

There is illustrated in Fig. 7 an arrangement of the system wherein a circuit independent of the feeder-circuit is used, the current being supplied by a battery a. If the battery is sufficiently strong, the circuit may be grounded, or, as indicated by the dotted line b, may be a complete metallic circuit. So, too, the circuit may be closed by means of a clock-actuated switch c, placed in the line, instead of being closed manually. It is manifest that the auxiliary registering device may be located at any desired point, it being merely a question of running the line. Again the system may be employed for the purpose of ascertaining whether or not the main meters are running properly. For instance, a series of such auxiliary registers might be installed in a station or substation and connected up with the various meters of the consumers, when upon closing the control circuit the auxiliary registers would be operated, providing, of course, the current was being used. Under this arrangement it is possible to determine the consumption of current or energy of any particular consumer without the necessity of leaving the station, in which instance, of course, the switch must be kept closed at all times. This may be of advantage in connection with substations where it will take only a relatively-short control-circuit to bring about the desired result.

In Fig. 8 there is illustrated a system wherein a number of service-meters are connected to a double series of auxiliary meters located at a suitable point, such as a substation, whereby the reading of each service-meter may be secured both for the period covering the peak of the load and also the remainder of the period or twenty-four hours in which the minimum charge is to be made. In this figure, 1, 2, 3, and 4 represent a series of service-meters adapted and designed to be located on the premises of the consumer or current-taker, said meters being connected through wires K to a series of double-throw switches 5, 6, 7, and 8, one series of contacts 9, 10, 11, and 12 of the switches being in circuit with a series of auxiliary meters 13, 14, 15, and 16, while the other series of switch-contacts 17, 18, 19, and 20 are in circuit with a second series of auxiliary meters or registering devices 21, 22, 23, and 24, each register in turn being connected upon its opposite side to the bus or feeder 25. From this it will be seen that the attendant at the main station or substation in which the auxiliary meters are located may by throwing the switches bring either of the series of auxiliary meters into circuit, so that said auxiliary meters may be caused to register for a predetermined period, the current passing through the service-meter. When said period has elapsed, the switches are thrown over, so

as to bring them into contact with the other switch-terminals, thereby throwing in the other auxiliary meters and registering the current for the balance of the day or period.

- 5 For instance, if it be desired to measure the current passing through the service-meter 1 during the period of maximum load all that is necessary for the operator or attendant to do is to throw switch 5 so as to bring it in contact with switch member or contact 9, thereby bringing the meter or auxiliary registering-meter 13 into circuit. When the period of maximum load has passed, the operator reverses the switch, bringing it into contact with switch contact or block 17, which will cause the meter 21 to be operated, registering the consumption of current during the period of minimum load. Thus it is with each of the meters 2, 3, and 4. It is manifest
- 10 that any mechanism or device may be employed whereby the series of contacts between the meters 13, 14, 15, and 16 may be closed simultaneously and automatically and after a stated period reversed, so as to bring the contacts 17, 18, 19, and 20 into circuit.
- 15
- 20
- 25

It will be seen that the invention is susceptible of many uses, of which a few have been set forth, and it is not desired to limit the system to any particular adaptation, though it will be found especially applicable to the double metering system, as first pointed out.

The system may be employed in connection with direct and alternating currents and with both at once if circuit is independently established, as in Fig. 7.

While the invention is primarily designed for use in connection with electric meters, still it is obvious that the make-and-break mechanism may be actuated by any form of meter or by measuring devices of other classes, such as gas-meters, water-meters, rotating shafts, and the like.

Having thus described my invention, what I claim is—

- 45 1. The combination of a meter; an electric circuit; a make-and-break device for the circuit operated by said meter; an electrically-actuated recording device in said circuit; and means for closing and opening the circuit, whereby the recording device may be brought into or thrown out of operation, as desired.
  - 50
  - 55
  - 60
2. In an electric-metering system, the combination of a meter arranged to operate and continuously record all the electric current or energy consumed; a second registering device; a circuit in which said second registering device is included; a make-and-break device for said circuit operated by the meter; and a switch for closing said circuit, whereby a reading for the total consumption of current or energy may be had, and a separate

and independent reading for a stated or determined period may also be secured.

3. In an electric-metering system, the combination of a series of meters arranged to operate and continuously record all of the electric current or energy consumed; a series of independent registering devices, one for each meter; a series of control-circuits in which said registering devices are included; make-and-break devices for said circuits operated by the meters; and means for closing and opening said circuits, and consequently throwing the registering devices, into and out of operation, as desired.

4. In an electric-metering system, the combination of a series of meters arranged to operate and continuously record all the electric current or energy consumed; two series of registering devices; a series of control-circuits in which said registering devices are included; make-and-break devices for said circuits operated by the meters; and means for throwing one or the other of said series of registering devices into circuit, substantially as and for the purpose described.

5. In an electric-metering system, the combination of a meter arranged to operate and continuously record all the electric current or energy consumed; two independent registering devices; control-circuits in which said registering devices are included; make-and-break devices for said circuits operated by the meter; and means for throwing one or the other of said registering devices into circuit, substantially as and for the purpose described.

6. In combination with an electric meter arranged to operate and continuously record all the electric current or energy consumed; a register; a circuit; a make-and-break device for said circuit operated by a moving member of the meter; an electrically-operated device included in the circuit for actuating the register; and a switch also included in the circuit.

7. In combination with an electric meter arranged to operate and continuously record all the electric energy or current consumed; a register; a circuit; a make-and-break device for said circuit operated by a moving member of the meter; an electromagnet included in the circuit; a pallet carrying an armature, said pallet being arranged to act upon and move a wheel carried by the register; and a switch included in the circuit.

In testimony whereof I have signed my name to this specification in the presence of two subscribing witnesses.

FREDERIC E. TOWN.
